Adrian Phillips, Bronx, N. Y., assignor, by mesne assignments, to Baldwin-Lima-Hamilton Corporation, Philadelphia, Pa., a corporation of Pennsylvania

Application October 18, 1955, Serial No. 541,133

11 Claims. (Cl. 209—72)

This invention relates to means for checking the condition of the bore of tubing for such factors as straightness and the presence of obstructions.

In inspecting tubing for straightness, it is often stipulated that a mandrel or drift of predetermined length and outside diameter be successfully passed through the tube. Heretofore this has been accomplished in makeshift ways, for example, by manually placing the mandrel in the tube and introducing compressed air by means of a flexible hose with a manually controlled valve. Another method consisted in pushing the mandrel through the tube by mechanical means and withdrawing it from the end into which it was fed. These methods were slow and depended almost entirely upon the skill of operators.

It is therefore one of the principal objects of this invention to provide a tube inspecting machine which is rapid in its action and is substantially independent of operators. A much larger capacity of tubing inspection may thus be obtained with a greater degree of precision.

It is a further object of this invention to provide a machine as set forth above which is capable of checking the interior of the tubes for obstructions, and removing scale and other foreign matter from the inner surface.

Further objects and advantages of this invention will become apparent in the following detailed description thereof.

In the accompanying drawings,

Fig. 1 is a side elevation, with parts broken away, of a tube inspecting machine embodying one form of this invention, parts such as feeding and discharging mechanisms being omitted.

Fig. 2 is a plan view of the Fig. 1 machine.

Fig. 3 is an enlarged section taken substantially on the line 3—3 of Fig. 2 disclosing the tube clamping mechanism.

Fig. 4 is an enlarged section taken on the line 4—4 of Fig. 2 disclosing the mandrel supporting and feeding mechanism.

Fig. 5 is an enlarged section taken on the line 5—5 of Fig. 2 disclosing the mechanism for delivering the mandrels to a conveyor.

Fig. 6 is a section similar to Fig. 3 but shows the mechanism for feeding tubes to the inspection position and removing tubes therefrom after inspection.

Fig. 7 is a view of certain parts of Fig. 6 in another operating position.

Fig. 8 is an enlarged section disclosing details of the air head valve.

Fig. 9 is an electric schematic diagram disclosing the sequence of operations of the Figs. 1 to 8 mechanisms.

Referring to Figs. 6 and 7 it will be seen that a supply of tubes 10 is maintained upon a suitable delivery platform 11 inclined so as to tend to feed the tubes to a cradle 14 in the upper end of a stand 15. Cradle 14

extends across a similar stand 15' which serves for clamping the tube (see Fig. 3). Feeding of the tubes is controlled by an escapement 16 at the upper end of a lever 17 pivoted at 18 to the outer end of a piston rod 19 operating in a double-acting cylinder 20 swivelled at 21 on a fixed support 22. More than one feeding mechanism may be provided along the length of the tube. The starting position is shown in Fig. 7. As indicated in Fig. 9, a source of electric power 101 is connected to feed lines 102, 103 which are in turn connected to various control lines arranged in parallel. To start operation of the machine, a two-position push button 12 is actuated to complete a circuit through a set of contacts 100 to energize a solenoid valve 23, with two-position snap switch LS-1 and normally closed contacts 110A being in closed condition and all other control circuits being open. Piston 19 will then be drawn to the right (in Fig. 6). The tube 10 on escapement 16 is fed to the left, and rolls down (see Fig. 7) until it strikes a member 24 which has been moved into its path by reason of the pivotal connection at 25 of a bell crank 26 of which member 24 forms one arm. The bell crank is pivoted at 26' on the stand 15. Arm 24 has a curved face 24' which is adapted to remove a finished tube from cradle 14 during upward movement of the arm.

The movement of the piston rod 19 to the right will cause limit switch LS-1 to be opened mechanically by means of projection 27 to break the circuit through the solenoid valve 23 (see Fig. 9). The valve is double-acting and is automatically returned to its reverse position where it causes piston 19 to be moved to the left to its initial position. This causes the bell crank 26 to be swung in a direction to move arm 24 out of the path of the tube 10 held by it, thus allowing the tube to roll onto stand 15 and into cradle 14 provided therefor. The escapement 16 now engages the next tube 10' which will be fed when solenoid valve 23 is again energized in the cycle of operation after the tube in position on cradle 14 has been inspected and removed from the machine. On completion of the return stroke of piston 19, switch LS-1 is closed by projection 28 but this will have no immediate effect as explained herein-after.

In rolling into position on cradle 14, the tube 10 momentarily closes a normally open switch LS-2 (see Figs. 6 and 9) before the piston 19 has completed its return stroke. This energizes a master relay 110 which controls the subsequent operation of the machine. Closing of relay 110 will cause it to open normally closed contacts 110A, close normally open contacts 110B, 110C and 110D, open normally closed contacts 110E, and close normally open contacts 110F.

Opening contacts 110A will prevent premature starting of another cycle by the tube feeding mechanism.

Closing contacts 110B will establish a holding circuit to keep master relay 110 energized as long as desired after the tube has rolled over switch LS-2, allowing the latter to open.

Closing of contacts 110C will close the circuit through solenoid valve 32 controlling the pressure within a double-acting cylinder 33 (see Fig. 3) to actuate its piston 34 to swing a frame 35 around a pivot 36 on clamping stand 15' from the dotted line to the full line position. The frame 35 carries a double-acting cylinder 38 at its upper end. As it reaches its vertical position, the frame closes a normally open switch LS-3. Since contacts 110D have been closed by master relay 110, a solenoid valve 39 will be energized to cause piston 40 to be moved out of cylinder 38 and bring a clamping head 41 into

firm engagement with the tube 10 in testing position on cradle 14.

Closing of contacts 110D and switch LS-3 will further close the circuit through a solenoid valve 44 controlling the pressure within a double-acting carriage feed cylinder 45 (see Fig. 1) to cause piston rod 46 to be moved to the right (in the drawings) to move a drift or mandrel toward and into the opening of tube 10. For this purpose, the piston rod 46 is pivotally connected to a structure such as a carriage 47 riding by means of upper and lower rollers 48 on beams 49. The carriage 47 supports a cradle 50 (see Fig. 4) upon which has been placed (in a manner to be described) a drift or mandrel 51. The movement of rod 46 and carriage 47 toward the right will cause the mandrel which has a bevelled forward end to engage and enter the tube, the rear end of the mandrel being engaged by an air head 54 mounted on the carriage. The cradle 50 is slightly below tube 10 so as not to strike it. Continued movement of the carriage toward the right will cause the air head 54 to engage and close the entrance to tube 10 after the mandrel is fully positioned therein. Continued motion of the carriage will move compressed air valve 55 towards the air head 54 against the pressure of spring 56 (see Fig. 8) so that in effect plug 57 will be lifted from its seat. A tubular member 58 is screwed onto the plug, and the openings 58' thereof will be brought into registry with inlet port 55' to admit compressed air through tubular portion 58 against mandrel 51 in the interior of the tube 10. The compressed air will drive the mandrel through tube 10 if the tube is sufficiently straight and free of obstructions.

The carriage 47 in its initial retracted position maintains open a switch LS-4 against the action of a spring 59. As the carriage is operated to the right, spring 59 closes switch LS-4. This switch and contacts 110-E (now open) control a valve 44' which tends to return the carriage to initial position, but is not effective until relay 110 causes contacts 110-E to close again. Thus premature return of the carriage 47 is prevented.

Since the forward movement of carriage 47 has allowed switch LS-4 to be closed, a circuit is established (see Fig. 9) through a solenoid 60 to control the pressure within a double-acting, mandrel feeding cylinder 61 (see Fig. 4) to cause a piston 62 to be returned within the cylinder. This will operate an escapement 63 to advance the next mandrel 51' to an intermediate position.

Closing of contacts 110F by relay 110, with switch LS-8 and contacts 120B being in closed condition, energizes a timer 140 which is adapted to take control of the operations in the event that a mandrel does not pass through tube 10 in a predetermined time interval after relay 110 has been energized by the closing of switch LS-2 and contacts 110F as the tube rolls onto the cradle 14. However, if the mandrel does come through the tube within the predetermined time, the timer 140 is rendered ineffective, as will be described.

Condition 1.—The mandrel passes through the tube

If the mandrel passes through the tube, it will strike and momentarily close a normally open switch LS-5 mounted on a back stop 70 (see Figs. 1 and 5). The mandrel will then drop to a lower level 71 (see Fig. 5) where it rolls upon a conveyor belt 72 to be fed to the mandrel storage. The momentary closing of switch LS-5 sets into operation the following changes in the electrical scheme as shown in Fig. 9: A relay 120 is momentarily closed. This will momentarily open normally closed contacts 120A to deenergize master relay 110. Deenergization of relay 110 accomplishes the following:

(a) Contacts 110B are opened to break the holding circuit through relay 110.

(b) Contacts 110C are opened to deenergize valve 32 and swing frame 35 down, opening switch LS-3.

(c) Contacts 110D are opened to deenergize valve 39 and release clamp 41. Also valve 44 is opened, connecting cylinder 45 to exhaust.

(d) Contacts 110E are closed, and since normally closed switch LS-4 is closed, the solenoid valve 44' is energized to return the carriage to starting position where it opens LS-4 to deenergize valve 44'. Air valve 55 will close automatically. Opening LS-4 further deenergizes valve 60, and piston 62 makes a forward stroke to feed mandrel 51' to the carriage.

(e) Contacts 110A are closed to close the circuit through solenoid valve 23. Arm 24 moves upward and its face 24' will push the inspected tube out of the cradle 14 so that it rolls upon discharge table 89. The next tube is fed to the cradle as described hereinbefore and starts the next cycle when rolling over switch LS-2.

The momentary closing of relay 120 by switch LS-5 also accomplishes the following: Contacts 120B which are normally closed are momentarily opened. This will deenergize timer 140 and break the holding circuit through contacts 140C, contacts 110F having also been opened when relay 110 was deenergized.

The mandrel is moved backward by the conveyor 72 to an inclined platform 75 (see Fig. 4) at the forward end of the machine, from which it will roll into a swivelled cradle 76. Just before dropping into the cradle the mandrel will momentarily close a normally open switch LS-6 with switch LS-7 being normally closed, to energize a relay 130.

The latter accomplishes the following:

(a) Closes normally open contacts 130A to complete a holding circuit.

(b) Closes normally open contacts 130B which will energize solenoid valve 80 of a single-acting cylinder 81 to lift piston 82 and the swivelled cradle 76. The mandrel on cradle 76 is thus lifted to the storage platform 77. The mandrel is delivered to the platform by causing cradle 76 to strike an abutment 78 to tilt the cradle so that the mandrel rolls upon the platform which cooperates with the escapement 63.

(c) In rolling on to platform 77, the mandrel momentarily opens normally closed switch LS-7 which will deenergize relay 130.

Deenergization of relay 130 will accomplish the following:

(a) Contacts 130A are opened to break the holding circuit.

(b) Contacts 130B are opened to deenergize valve 80 and allow piston 82 to descend by gravity to lowered position.

Condition 2.—The mandrel is not ejected

If the mandrel is not ejected due to an unsatisfactory condition of the tube, obviously switch LS-5 is not actuated. Therefore, timer 140 completes its time cycle and accomplishes the following:

(a) Contacts 140B are opened and relay 110 is deenergized. (In the case of a good tube, this function is performed by the mandrel striking and closing switch LS-5 which energizes relay 120 to open contacts 120A.) Deenergizing relay 110 sets into operation all of the steps hereinbefore described as resulting therefrom, i. e., the holding circuit through relay 110 is opened, frame 35 is swung down, clamp 41 is released, cylinder 45 is connected to exhaust, solenoid valve 44' is energized to return the carriage, a mandrel is fed to the carriage, and contacts 110A are closed to energize solenoid valve 23 to cause the tube feeding mechanism to push the inspected tube out of the cradle 14 to the discharge table and feed the next tube to the cradle. Although deenergization of relay 110 opens contacts 110F, this does not result in deenergization of timer relay 140 because of the holding circuit completed by contacts 140C.

(b) Contacts 140A which are normally open, are closed. This energizes solenoid valve 83 of a single-acting latch operating cylinder 85 (see Fig. 6) to withdraw a latch 86 against spring pressure from a reject table 87 pivoted at 88 on the fixed discharge table 89.

(c) Closing of contacts 140A also energizes a solenoid valve 84 of a double-acting cylinder 90 whose piston 91 is connected to reject table 87 to pull the table downwardly to the dotted line position and provide a gap 95 large enough for the unsatisfactory tube to roll down on the inclined table 87.

When the rejected tube has passed through gap 95, it will roll onto inclined reject platform 96. In the course of its movement along this platform it will momentarily open normally closed switch LS-8. This will accomplish the following:

(a) It will deenergize timer 140.

(b) Deenergizing timer 140 will break the holding circuit therethrough by opening contacts 140C.

(c) It will open contacts 140A to deenergize latch cylinder solenoid 83 so that latch 86 will return to its forward position under spring pressure. Opening of contacts 140A will further deenergize solenoid 84 of reject cylinder 90, which will cause piston 91 to lift reject table 87 to the full line position in Fig. 7 so that latch 86 will snap into a recess in the table to lock it.

(d) It will close contacts 140B to restore the elements to starting positions where relay 110 can again be energized.

As the bad tube rolls off the reject table 96 it will further close a normally open switch LS-9 momentarily. Closing of this switch is adapted to accomplish the same result as the momentary closing of switch LS-2 as both switches are connected in parallel. The closing of switch LS-9 serves to ensure that the next cycle starts properly after discharge of an unsatisfactory tube. This safeguard is necessary since switch LS-2 will be ineffective in case timer-controlled contacts 140B are still open at the time the next tube strikes switch LS-2. If, however, the latter switch starts the next cycle properly, switch LS-9 will have no effect thereon.

Wherever reference is made in the specification and claims to the inspection of tubes, it is to be understood as including the cleaning of tubes since the mandrel may be a cleaning utensil. The expression tubes as used in the specification and claims is intended to include pipes and other tubular objects.

Having described my invention, what I claim and desire to secure by Letters Patent is:

1. A machine for inspecting tubes, comprising a support for maintaining a tube in position for inspection, a structure for supporting a mandrel, said structure having means for projecting the mandrel supported thereon, means for moving the mandrel supporting structure and the tube relative to each other so that they approach each other, and means rendered effective upon said approach for actuating the mandrel projecting means to propel said mandrel through the tube.

2. A machine for inspecting tubes, comprising a support for maintaining a tube in position for inspection, a carriage for supporting a mandrel, the carriage having means for projecting the mandrel supported thereon, means for operating the carriage toward the tube support, and means rendered effective by approach of the carriage to the tube support for actuating the mandrel projecting means to propel said mandrel through the tube.

3. A machine for inspecting tubes, comprising a support for maintaining a tube in position for inspection, means for feeding a tube to the support, a carriage for supporting a mandrel, means for feeding a mandrel to the carriage, the carriage having means for projecting the mandrel supported thereon, means for operating the carriage toward the tube support so as to cause the mandrel to engage the tube, control means actuated in response to the feeding of a tube to the tube support for rendering the carriage operating means effective, and means for actuating said mandrel projecting means upon approach of the carriage to the tube support to propel said mandrel through the tube.

4. A machine for inspecting tubes, comprising a sup-

port for maintaining a tube in position for inspection, means for feeding a tube to the support, a carriage for supporting a mandrel, a mandrel storage, means for feeding a mandrel from the storage to the carriage, the carriage having means for projecting the mandrel supported thereon, means for operating the carriage toward the tube support to cause the mandrel to engage the tube, control means actuated in response to the feeding of a tube to the tube support for rendering the carriage operating means effective, means rendered effective by approach of the carriage to the tube support for actuating the mandrel projecting means to propel said mandrel through the tube, and means for returning the mandrel to the mandrel storage after it has been propelled through the tube.

5. A machine for inspecting tubes, comprising a support for maintaining a tube in position for inspection, means for feeding a tube to the support, a carriage for supporting a mandrel, a mandrel storage, means for feeding a mandrel from the storage to the carriage, the carriage having means for projecting the mandrel supported thereon, means for operating the carriage toward the tube support to cause the mandrel to engage the tube, a movable frame, means for moving the frame to effective and ineffective positions, clamping means carried by the frame and operable to effective and ineffective positions into and out of engagement with the tube on the tube support, control means actuated by the feeding of a tube to the tube support for actuating the frame to effective position, further control means actuated by the movement of the frame to effective position for operating the clamping means to effective position into engagement with the tube on the tube support and for rendering the carriage operating means effective, means rendered effective by approach of the carriage to the tube support for actuating the mandrel projecting means to propel said mandrel through the tube, and means for returning the mandrel to the mandrel storage after it has been propelled through the tube.

6. A machine for inspecting tubes, comprising a support for maintaining a tube in position for inspection, means for feeding a tube to the support, a clamping device operable to effective and ineffective positions for engaging and disengaging a tube on the support, a carriage for supporting a mandrel, means for feeding a mandrel to the carriage, the carriage having means for projecting the mandrel supported thereon to propel it through the tube, means for operating the carriage toward and away from the tube support, control means actuated in response to the clamping of a tube on the tube support for rendering effective the carriage operating means to move the carriage toward the tube support, and additional control means actuated upon passage of the mandrel through the tube for rendering effective the carriage operating means to move the carriage away from the tube support.

7. A machine for inspecting tubes as specified in claim 6, including control means actuated by the feeding of a tube to the tube support for actuating the clamping device to effective position into engagement with the tube on the tube support, and means actuated by said additional control means for actuating the clamping device to disengage the tube.

8. A machine for inspecting tubes as specified in claim 6, including a reject mechanism for discharging an unsatisfactory tube, timing means for actuating said reject mechanism, means for rendering the timing means effective to actuate the reject mechanism upon failure of the mandrel to pass through the tube in a predetermined time, and means actuated by said additional control means for rendering the timing means ineffective to actuate the reject mechanism upon passage of the mandrel through the tube.

9. A machine as specified in claim 8, in which the timing means is adapted to actuate the carriage operating means to move the carriage away from the support, and means for rendering the timing means effective to move the

carriage upon failure of the mandrel to pass through the tube in a predetermined time.

10. A machine as specified in claim 9, in which the timing means is adapted to actuate the clamping device to disengage the tube, and means for rendering the timing means effective to actuate the clamping device to disengage the tube upon failure of the mandrel to pass through the tube in a predetermined time.

11. A machine for inspecting tubes, comprising a support for maintaining a tube in position for inspection, a carriage for supporting a mandrel, the carriage having means for projecting the mandrel supported thereon, means for operating the carriage toward the support to cause the mandrel to engage the tube, means rendered effective by approach of the carriage to the tube support for actuating the mandrel projecting means to propel said

10
